SHOE SOLE OR SIMILAR ARTICLE

Anthony A. Mattos, Bristol, R.I., assignor to Marbill Company, Providence, R.I., a corporation of Rhode Island

Filed Sept. 23, 1965, Ser. No. 87,125

Term of patent 14 years

(Cl. D7—5)

FIG. 1 is a bottom plan view of a shoe sole, showing my new design;

FIG. 2 is a cross sectional view taken on the line 2—2 of FIG. 1; and

FIG. 3 is a side elevational view thereof.

I claim:

The ornamental design for a shoe sole or similar article, substantially as shown.
